UNITED STATES PATENT OFFICE.

ANNA BROWN, OF VANCOUVER, WASHINGTON.

BED.

1,104,619.

Specification of Letters Patent. Patented July 21, 1914.

Application filed May 1, 1914. Serial No. 835,705.

To all whom it may concern:

Be it known that I, ANNA BROWN, a citizen of the United States, residing at Vancouver, in the county of Clarke and State of Washington, have invented new and useful Improvements in Beds, of which the following is a specification.

This invention relates to beds and more particularly to extension beds and to a means 10 for supporting the extension.

In the type of device most commonly used at present the side extensions which are used for converting the cot or bed from a single to a double one have pivoted thereto diagonally extending braces which engage the framework of the bed to hold them in horizontal position. This structure, however, does not prevent the overturning of the bed when any weight is applied adjacent the 20 outer edge of the extension.

It is the object of this invention to avoid this difficulty and, broadly speaking, the device consists of suitable supporting members or legs which may be folded beneath 25 the side piece of the extension so as to be out of the way when the extension is folded alongside of the frame of the bed.

Another object of the invention resides in the provision of novel locking means for 30 holding the legs or supporting members in folded or extended position.

Further objects of the invention will appear as the following description is read in connection with the accompanying drawing, 35 which forms a part of this application, and in which:—

Figure 1 is a side elevation of a bed showing the supporting legs for the extension in operative position. Fig. 2 is a detail top 40 plan view. Fig. 3 is a vertical longitudinal sectional view taken on the line 3—3 of Fig. 2. Fig. 4 is a view similar to Fig. 3 showing the legs in folded position. Fig. 45 5 is a transverse sectional view on the line 5—5 of Fig. 2.

Referring more particularly to the drawing, the bed or couch proper consists of a frame 1 which carries the usual supporting springs or spring fabric 2 and is supported 50 in the usual manner by the legs 3. Pivots connected to the frame 1 are U-shaped extensions consisting of end and side bars 4 and 5, the latter being centrally apertured on its upper side, as shown at 6, for a purpose to be hereinafter described. As is usual, the spring fabric is connected to the

side and end bars of the extensions and simply forms a continuation of that which is bridged across the bed or couch proper.

The frame 1 and the extensions are, as 60 usual, constructed of angle iron although this may be substituted by channel iron or any other material without departing from the spirit of the invention.

In order to hold the extensions, which are 65 adapted to fold against the legs 3, in horizontal position there is pivoted to the vertical portions of the side members 5 supporting legs 7 which are adapted to lie against the vertical portions of said side members 70 and beneath the horizontal portions thereof so as to be wholly concealed when not in use. These legs are also adapted to extend at right angles to the side members so as to lie in a vertical plane and rest upon the 75 floor and may, if desired, be supported with casters, as shown.

In order to operate the legs 7 so as to throw them from folded to extended position or vice versa there is journaled in the 80 vertical portions of the side members 5 a shaft 8 having keyed upon its outer end an operating handle or button 9 and upon its inner end a double lever 10 which is connected to the legs 7 by means of the links 11. 85 This lever has its ends operating through the slot 6 and is locked in horizontal position with the legs folded or in extended position by means of a locking plate 12 which is pivoted to the horizontal portion of the side 90 members and adapted to extend across and close the slot 6. Each of the links 11 have downwardly turned ends 13 which engage in diagonal slots 14 so as to compensate for the difference in radius of the links and that of 95 the legs.

When the legs are in folded position and it is desired to throw them to operative position the locking plate is turned to the position shown in dotted lines in Fig. 2 and the operating handle or button turned clockwise which gives the double lever 10 a similar movement. The links are thus moved in opposite directions, their downturned ends sliding in the slots until the end of said slots 100 is reached, at which time the legs will be moved outwardly as will be readily understood, until the lever has been reversed, at which time the legs will be in vertical position and held against movement irrespective 110 of the position of the links in the slots. The locking plate is then thrown to operative po-

sition again across the slots which prevents movement of the double lever 10.

What is claimed is:

1. In a bed, an extension pivoted thereto, 5 supporting legs for holding the extension in horizontal position, means for throwing the legs to operative or inoperative positions, and means for securing the operating means against operation when the legs are in either 10 position.
2. In a bed, an extension pivoted thereto, legs pivoted to the extension and adapted to fold thereon or support the extension in horizontal position, means for throwing the 15 legs to extension supporting position or folding them upon the extension, said means comprising in part a double lever, and means for locking the double lever against movement when the legs are in either position.
- 20 3. In a bed, an extension pivoted to the bed, supporting legs pivoted to the extension and adapted to fold thereon, a double

lever pivoted to the extension and connected to the legs, means for operating the lever to throw the legs to operative or inoperative 25 position, and means for locking the lever against movement.

4. In a bed, an extension pivoted to the bed, supporting legs pivoted to the extension and adapted to fold thereon, a double 30 lever pivoted to the extension and connected to the legs, means for operating the lever to throw the legs to operative or inoperative position, and a locking plate pivoted to the extension adapted to be arranged in the 35 path of movement of the lever whereby the legs will be locked in operative or inoperative position.

In testimony whereof I affix my signature in presence of two witnesses.

ANNA BROWN.
